UNITED STATES PATENT OFFICE.

ANTON KOHLENBRAND, OF BUXTON, IOWA.

CURTAIN AND SHADE BRACKET.

1,333,425.

Specification of Letters Patent. Patented Mar. 9, 1920.

Application filed June 4, 1919. Serial No. 301,654.

To all whom it may concern:

Be it known that I, ANTON KOHLENBRAND, a citizen of the United States of America, residing at Buxton, in the county of Monroe and State of Iowa, have invented new and useful Improvements in Curtain and Shade Brackets, of which the following is a specification.

The object of the invention is to provide 10 a simple and relatively inexpensive curtain and shade roller bracket adapted for engagement with a window casing without the disadvantages incident to the engagement therewith of termination fastening means 15 serving in the ordinary practice to deface or mar the woodwork, and adapted to be applied, after the adjustment of its elements, in a single operation to a casing, regardless of the width or general contour thereof, in 20 a single operation, preparatory to mounting the shade roller and curtain pole thereon.

With these objects in view the invention consists in a construction and combination of parts of which a preferred embodiment 25 is illustrated in the accompanying drawing, it being understood that changes in form and proportion may be resorted to within the scope of the claim without departing from the principles involved.

30 In the drawing:

Figure 1 is a front view of the apparatus applied in the operative position to a window casing.

Fig. 2 is a detail view in perspective of 35 one end of the device.

Fig. 3 is a detail sectional view taken in the plane of one of the terminal bearing elements of the extension bar.

Fig. 4 is a detail sectional view through 40 the telescoping joint between the members of said bar.

The bracket consists essentially of an extension bar 10 comprising relatively movable and adjustable members 11 and 12 connected by a telescoping joint by providing one of the members with a sleeve 13 for the reception of the extremity 14 of the other member, a coiled spring 15 being arranged to embrace said telescoping portions of the 50 members and being terminally connected therewith respectively by pins 16 engageable with series of transverse openings 17 so that by changing the locations of the pins the tension of the spring may be varied 55 to adapt the length of the bar to different widths of window casings. At their remote

extremities these bar members are provided with bearing elements or feet 18 from which may project pole supporting arms 19, while at their lower extremities said bearing feet 60 support channeled guides 19' having longitudinal slots 20 through which extend set screws 21, engaging ears 22 forming parts of the shade roller socket arms 23 and bearing plates 24 located within the channeled 65 guides and serving by the tightening of set screws, in combination with the ears 22, to clamp the guide and thus lock the roller bearing arm in an adjusted position. In other words, the interval between the roller 70 bearing arms at the extremities of the bracket may be varied to suit the length of the shade roller by loosening the set screws and thereby permitting the bearing arms to be moved longitudinally of the 75 guides 19, and after the desired adjustment has been secured, the tightening of said set screws will cause the bearing plates 14 and the ears 22 to clamp the wall of the guide and thus lock the arms in place. 80

After having determined the length of the shade roller to be mounted and having adjusted the bearing arms accordingly, the bracket may be attached to the casing by simply fitting the extension bar over the 85 upper edge thereof so as to bring the terminal bearing end 18 thereof in contact with the side surfaces of the frame as indicated in Fig. 1 whereupon the contractile force of the spring acting upon the members of 90 the extension bar will hold said bearing feet in place and thus properly position the pole and roller bearing elements. The arrangement of the extension bar above the upper edge of the casing serves to conceal it from 95 view within the room and at the same time prevents the downward displacement of the bracket by reason of excessive downward strain thereon, without necessitating any permanent means of fastening for engagement with the woodwork of the casing. 100

The invention having been described, what is claimed as new and useful is:

A curtain and shade roller bracket comprising an extension bar adapted to lie on 105 the upper edge of a window frame, the said extension bar being formed with terminal bearing feet to engage the upper side edges of the frames, channel shaped guides disposed in planes at right angles to the bearing feet and paralleling the main portion 110 of the extension bar, the said guides having

their flanges set in slots formed in the bearing feet, shade roller socket arms having their bases disposed transversely across the channel shaped guides and formed with 5 ears engaging the opposite sides of the guides, bearing plates set between the flanges of the guides, and screws passing through

the bases of the socket arms and threadingly engaging the plates, the channel shaped guides being formed in their webs with longitudinal slots through which the screws pass. 10

In testimony whereof I affix my signature.
ANTON KOHLENBRAND.
